IRONING DEVICE CARRYING REVERSIBLE PRESSING CLOTH

Filed April 8, 1949

FIG. 5.

SAMUEL G. SHAPIRO
INVENTOR.

BY -

ATTORNEY

UNITED STATES PATENT OFFICE

2,559,550

IRONING DEVICE CARRYING REVERSIBLE
PRESSING CLOTH

Samuel G. Shapiro, Philadelphia, Pa.

Application April 8, 1949, Serial No. 86,203

3 Claims. (Cl. 38—75)

1

The present invention relates to ironing devices for use in salesrooms, stores, show windows, at sales and display counters, and by salesmen on the road, repairmen at customers' homes, and the like, to put on the finishing touches, take out creases and put back into shape, wearing apparel, furs, fabrics, upholstery and a variety of other articles.

The principal object of this invention is to provide a novel and improved held-in-hand ironing device for the purposes mentioned, which carries its own pressing cloth adapted to present a dry surface for contacting the article to be ironed, and which will iron with moist heat.

Another object hereof is to provide a novel and improved pressing device of the type described associated with a pressing cloth or the like, adapted to have the surface thereof which sets against the heated iron, wetted, and presents only its dry surface against the article to be ironed, whereby the device will iron with moist heat.

Another object is to provide an ironing device of the kind set forth, which may carry a comb, brush or other suitable attachments for use to accomplish operations incidental to ironing various articles, for instance those made of straight-haired fur as silver fox, mink, seal, beaver, mouton, and fabrics as mohairs, velours, velvets and fabrics of all kinds.

A further object of this invention is to provide an ironing device of the character described, which is of novel and improved construction, having a new mode of operation, and is reasonably cheap to manufacture, easy and convenient to use and efficient in operation.

Other objects and advantages will become apparent as this disclosure proceeds.

In the accompanying drawings forming part of this specification, similar characters of reference indicate corresponding parts in all the views.

Fig. 1 is a front view of an ironing device embodying the teachings of this invention.

Fig. 2 is a perspective view of the pressing cloth structure included in such embodiment.

Fig. 3 is a perspective view of ball joint parts used to swivelly mount an end of the pressing cloth onto an end of the pressing iron.

Fig. 4 is an enlarged fragmentary view of a part of Fig. 1, showing the ball joint assembled.

Fig. 5 is a side view of Fig. 4, minus the pressing cloth.

In the drawings, the numeral 15 designates generally an electrically heated pressing iron, shown to be of elongated form and trapezoidal in cross section. From one end of this pressing

2

iron 15, there extends a tubular member 16 which terminates in a handle 17. Depending upon the nature of the work to be done, this iron may be used with or without the pressing cloth structure 22. To accomplish the mode of operation as herein taught, the pressing cloth 22 is swivelly mounted at one of its ends to the other end of the iron body 15, in a manner to be easily detachable therefrom. For such purpose a ball joint means may be provided as is shown in Fig. 3. Component 18 has suitable socket 18' with communicative slot 18'', to removably receive the ball element 19 which is at the end of a shank 20; the other end of said shank being anchored in a rod piece 21, midway between the ends of such piece.

The pressing cloth 22, is in the form of a strap, which may be of multi-ply canvas material, slightly wider than the face of the ironing member 15. Extending centrally from one end of said strap 22, is a shank 20 having a ball head 19. The other end of the strap 22 terminates in a stiff ring 23, into whose opening 24 is received the hook 25. It is practical to have the rod piece 21 positioned in the fold at the end of the strap 22, which end is gripped by an edging 14 to hold the strap plies 22' and 22'', in lateral extension.

On the tube 16, is secured a collar member 26, which carries a bell-crank lever 27, pivoted at 28. The hook 25, is pivotally carried on said lever 27, at 29, which is at the end of the short arm of said lever.

In operation, the pressing cloth strap 22 is mounted taut on the pressing iron as shown in Fig. 1. The ironing member 15, is of course heated. Initially, both surfaces of said pressing cloth strap 22 are dry. Now, the exposed surface 22'' is wetted in any suitable manner, as for instance, setting the device down on a pressing sponge pad which is wet. Now held in hand or on suitable stand, the device is dealt with as follows. The lever 27 is swung downwardly, whereupon hook 25 loosens its hold on strap end 23, and the strap 22 may be removed from said hook. The wetted surface 22'' is set against the underside of the ironing member 15; the ball joint connection, permitting the swivel movement of the strap 22. Now the strap end 23 is positioned in engagement with the hook 25, and finally lever 27 is swung upwardly, whereupon the strap 22 is pulled taut. The length of the strap 22, is of suitable dimension to accomplish this tautness. If desired, a tension spring 30 may be included to maintain lever 27 against the handle 17.

It is evident that pressing is done with the dry

surface 21' of the pressing cloth strap 22, and that the article being ironed, will be subject to moist heat. As soon as the steaming action stops due to the drying up of the surface 22'', the device is again set on the wet sponge pad, this time to wet the surface 22' of the pressing cloth strap 22. Again the said strap is released from off the hook 25, and swiveled so that the wetted surface 22' is against the surface of the hot ironing member 15. After the strap 22 is again properly mounted taut, pressing is done with the now exposed dry surface 22'' of the pressing cloth strap 22, and the article being ironed will be subjected to moist heat. This operation is repeated as long as ironing need be done, except, when of course the pressing cloth strap is entirely detached, and pressing is done directly by contacting the pressing iron onto the article to be ironed.

Along the top of the iron 15, there may be a channel 31, in which may be mounted a detachable brush or comb 32, or other desired attachment to be held secured by suitable means as the set screw 33.

This invention is capable of numerous forms and various applications without departing from the essential features herein disclosed. It is therefore intended and desired that the embodiment herein be deemed illustrative and not restrictive and that the patent shall cover all patentable novelty herein set forth; reference being had to the following claims rather than to the specific description herein to indicate the scope of this invention.

I claim:

1. In a device of the character described, the

combination of a pressing iron having a handle, a pressing cloth positioned on the pressing surface of the iron and extending beyond two opposite ends of said surface, one end of said pressing cloth being swivelly connected to one of such ends of the iron, above the pressing surface of the iron, whereby said pressing cloth may be swivelled to position either surface thereof against the pressing surface of the iron and means carried on the iron detachably engaging the second end of said pressing cloth above the pressing surface of the iron, to maintain said pressing cloth against the pressing surface of the iron.

5 15 2. A device as defined in claim 1, wherein the pressing iron is of elongated form and the pressing cloth mentioned is in the form of a strap; the narrow ends of the strap extending beyond the narrow ends of the pressing iron and associated therewith as mentioned.

20 25 3. A device as defined in claim 1, wherein the last mentioned means is movably mounted on the handle whereby when moved away from the swivelled end of the pressing cloth, said means will pull and maintain the pressing cloth taut against the pressing surface of the iron.

SAMUEL G. SHAPIRO.
